UNITED STATES PATENT OFFICE

2,680,002

BELT TIGHTENER

Lewis S. Farner, New Kensington, Pa.

Application November 24, 1952, Serial No. 322,195

1 Claim. (Cl. 254—55)

1

This invention relates to new and useful improvements and structural refinements in belt tighteners, and the principal object of the invention is to provide an apparatus of the character herein described, which may be conveniently and effectively employed for drawing together the ends of a belt, such as for example, a conveyor belt, immediately prior to connecting the ends of the belt together.

Some of the advantages of the invention reside in its simplicity of construction, in its efficient and dependable operation, and in its adjustability to accommodate belts of different thicknesses and widths.

With the above more important objects and features in view, and such other objects and features as may become apparent as this specification proceeds, the invention consists essentially of the arrangement and construction of parts as illustrated in the accompanying drawings, in which:

Figure 1 is a side elevational view of the invention, the same being partially broken away so as to reveal its construction;

Figure 2 is a top plan view of the invention, and

Figure 3 is a transverse sectional view, taken substantially in the plane of the line 3—3 in Figure 2.

Like characters of reference are employed to designate like parts in the specification and throughout the several views.

Referring now to the accompanying drawings in detail, the belt tightener is designated generally by the reference character 10 and embodies in its construction a pair of spaced, parallel belt clamping units 12, each consisting of a pair of superposed bars or straps 14, 16, which are provided in end portions thereof with sets of registering apertures 18 to selectively receive clamping bolts 20.

The straps 14, 16 of each clamping unit 12 are adapted to receive therebetween a belt 22 which is to be tightened, it being noted that the straps are substantially longer than the width of the belt, so that the bolts 20 are disposed at the outside of the longitudinal edges of the belt, as is clearly shown in Figure 3.

A pair of elongated, extensible and contractible jack members 24 extend between and are connected to the opposite end portions of the clamping units 12, each of these jack members including a rod 26 having a conventional jack device 28 adjustably positioned on one end portion thereof. The jack device 28 is actuated by means

2

of a suitable handle 30, the arrangement being such that when this handle is actuated in an oscillatory fashion, the jack device 28 travels along the rod 26 in the direction of the arrow 32 as shown in Figure 1.

The two jack devices 28 are provided with base plates 34 which, in turn, are equipped with downwardly projecting pins 36, the latter being receivable in the apertures 18 of the straps 14, 16 10 of one of the clamping units 12.

The free ends of the two rods 26 are provided with spacer blocks 38 which, in turn, are equipped with downwardly projecting pins 40 receivable in the apertures 18 of the straps 14, 16 of the other 15 clamping unit 12.

When the invention is placed in use, the units

12 are clamped by means of the screws or bolts 20 to the end portions of the belt 22 and by actuating the handles 30 of the two jack devices

20 28, the jack devices are caused to travel along the rods 26 toward the spacer blocks 38 as shown by the arrow 32, so that, in effect, the entire

clamping unit 12 to which the pins 36 are connected is drawn toward the other clamping unit

25 having the pins 40 engaged therewith. In that fashion, the ends of the belt are brought together and the belt is substantially tightened prior to connecting the ends thereof.

It is to be noted that since two of the members

30 24 are employed, one at each side of the belt, they may be individually and independently actuated, which will result in a longitudinal pulling as well as a lateral shifting action being imparted to the belt, so that the ends of the belt may be

35 properly longitudinally aligned.

It is believed that the advantages and use of the invention will be clearly understood from the foregoing disclosure and, accordingly, further description thereof at this point is deemed unnecessary.

40 However, since numerous modifications and changes will readily occur to those skilled in the art, it is not desired to limit the invention to the exact construction shown and described, and accordingly, all suitable modifications and equivalents may be resorted to, falling within the scope of the appended claim.

Having described the invention, what is claimed as new is:

50 A belt tightener of the character described comprising: pairs of clamping bars for receiving the end portions of a belt therebetween, said bars having spaced openings in the end portions thereof, bolts insertable selectively in the openings for securing the belt between the pairs of

bars, removable plates on one of the pairs of bars, depending anchoring pins on said plates engageable selectively in the openings of said one pair of bars for adjustably and removably securing said plates thereto, jack devices mounted on the plates and including slidably mounted rods paralleling the belt, said jack devices further including means for actuating the rods, depending spacers on one end portion of the rods resting on the other pair of bars, and depending pins 10 on said spacers engageable selectively in the openings in said other pair of bars for adjustably,

detachably and operatively connecting the rods thereto.
